UNITED STATES PATENT OFFICE.

OTTO UNZICKER, OF CHICAGO, ASSIGNOR TO ADOLPH SHOENINGER, OF LAKE VIEW, ILLINOIS.

SLED.

SPECIFICATION forming part of Letters Patent No. 349,827, dated September 28, 1886.

Application filed January 29, 1886. Serial No. 190,160. (No model.)

To all whom it may concern:

Be it known that I, OTTO UNZICKER, a citizen of the United States of America, residing at Chicago, in the county of Cook and State 5 of Illinois, have invented certain new and useful Improvements in Sleds, of which the following is a specification, reference being had therein to the accompanying drawings.

The object I have in view is to produce a 10 sled combining great strength with lightness, and that is neat and graceful in appearance.

For that purpose my invention mainly consists in forming the runners of cylindrical wooden rods, and in lining such runners with 15 semicircular iron curvilinearly extended at both ends to connect with the raves and cross-bars, also in round iron braces diagonally connecting the runners with the cross-bars of the sled, all as hereinafter more fully described 20 and specifically claimed.

In the accompanying drawings, Figure 1 represents a perspective view of the sled, the seat-board being removed; Fig. 2, a vertical cross-section of the same; and Fig. 3, a sectional 25 detail showing the connection of a cross-bar, brace, and rave by a single bolt.

Corresponding letters in the several figures of the drawings designate like parts.

A denotes the runners, and B the raves, both 30 being cylindrical wooden sticks.

C C' are the cross-bars, the ends of which are connected by the raves B. Upon these cross-bars C C' the seat-board D is secured. The runners A are lined on their bottom with 35 semicircularly-shaped iron bars E, extending at both ends beyond such runners, the forward extensions of bars E being curved upward and then to the rear, and their ends secured upon the front ends of raves B and their rearward extensions being curved up and forward, with their ends secured under the rear cross-bar, C'. A round iron brace, F, extends from each runner A diagonally to the under side of the opposite end of a cross-bar, C or C', in a 40 manner that such cross-bar is thus connected with and supported on the two runners by two such braces F crossing each other. These cross-braces are bent at f, to provide a long

bearing-surface for the cross-bars thereon, and thereby obtain additional strength. These 50 cross-braces also have eyes formed to their ends, to be secured upon the runners A each by a rivet, a, passed through the runner A, bar E, and through such eye of brace F. To each end of a cross-bar C C' is rigidly connected the end of a rave, B, of a bar, E, and a brace, F, by a single screw-bolt, b, passed through all these parts. The curved front ends of bars E are connected by a chain, G, as a handle, or for connecting a rope by which to 60 pull the sled. As will be readily seen, the bars E, forming the shoes for the runners, also brace the seat longitudinally, while the cross-rods F not only form strong supports for the seat of the sled, but lateral braces as well for 65 securely holding the runners in a proper parallel position relative to such seat.

Cylindrical runners are cheaper to manufacture than when made any other shape, and their appearance is light and neat, while the 70 semicircular bars inclosing their under surface will not only stiffen these runners to a great extent, but will also prevent their splitting with riveting.

What I claim is—

1. In a sled, the combination, with cylindrical runners, of semicircular bars forming shoes for these runners, and having curved extensions that connect with the raves and cross-bars of the seat portion of the sled, substantially as set forth.

2. In a sled, the combination of cylindrical runners, of semicircular bars forming shoes for these runners and having curved extensions that connect with the raves and cross-bars, and of iron cross-rods connecting the runners with the cross-bars and acting as supports and braces thereto, substantially as set forth.

In testimony whereof I affix my signature in presence of two witnesses.

OTTO UNZICKER.
